UNITED STATES PATENT OFFICE.

WILLIAM H. PERRY, OF CONCORD, NEW HAMPSHIRE.

DESIGN FOR A MONUMENT.

SPECIFICATION forming part of Design No. 22,577, dated June 27, 1893.

Application filed May 26, 1893. Serial No. 475,641. Term of patent 7 years.

To all whom it may concern:

Be it known that I, WILLIAM H. PERRY, a citizen of the United States, residing at Concord, in the county of Merrimac and State of 5 New Hampshire, have invented and produced a new and original Design for Monuments, of which the following is a specification, reference being had to the accompanying drawing.

My design consists more particularly in the 10 configuration of the shaft, the several forms of ornamentation of said shaft, the pedestal, and the base, and the character of the surfaces of different parts; which will be fully set forth in the following specification and 15 clearly illustrated in the drawing, accompanying and forming a part thereof.

Referring to the drawing by figures and letters of reference,—the base 1, has four vertical sides terminating at their tops in an 20 obtuse frustum of a pyramid 2. The pedestal 3, has four vertical sides terminating at their tops in an obtuse frustum 4, of a pyramid, and a raised tablet 5, may be formed upon one or more sides of the pedestal 3. 25 The shaft C, has for the main portion four vertical sides joined at their bottoms to the frustum, 4, and terminating at their tops in a slightly tapering convexed portion 7; the line dividing them being slightly arched on 30 the vertical sides of said shaft as seen at 8. The greater portion of the corners of said

shaft from their tops downward are chamfered as seen at 9. The corners of part 7 may be ornamented by the V grooves 10, if desired, and said part 7 terminates at its top 35 in an acute frustum of a pyramid 11, upon which rests an ornament 12, having a four sided pyramidal top 13.

Another feature of my design is the tablets 14, 15, and 16, upon each side of the shaft, 40 and which are designated by surfaces of a different character from the remainder of the shaft and are plainly illustrated by border lines having the configuration seen in the drawing. The tablets 16, meet each other at 45 their ends closing the chamfer 9 of the shaft. Other features of my design consist in the ornamentation of the different parts by surfaces of a different character which are designated by letters A, B, C:—A representing 50 rockwork, B, hammered work and C, polished work.

Having described my design, what I claim is—

The design for a monument substantially 55 as shown and specified.

In testimony whereof I affix my signature in presence of two witnesses.

WILLIAM H. PERRY.
